CLAIM

The ornamental design for a set of nursing breast pads as shown and described.

DESCRIPTION

FIG. 1 is a front perspective view of a set of nursing breast pads showing the new design;
FIG. 2 is a left view thereof;
FIG. 3 is a right view thereof;
FIG. 4 is a top view thereof;
FIG. 5 is a bottom view thereof;
FIG. 6 is a rear elevational view thereof;
FIG. 7 is a front perspective view of a set of nursing breast pads showing the new design;
FIG. 8 is a left view thereof;
FIG. 9 is a right view thereof;
FIG. 10 is a top view thereof;
FIG. 11 is a bottom view thereof; and,
FIG. 12 is a rear elevational view thereof.
The broken lines are for illustrative purposes only and forms no part of the claimed design.
